UNITED STATES PATENT OFFICE.

MICHAEL HARTNETT, OF MILTON, PENNSYLVANIA.

RAILWAY-TIE.

1,315,304.

Specification of Letters Patent.

Patented Sept. 9, 1919.

Application filed April 5, 1919. Serial No. 287,901.

To all whom it may concern:

Be it known that I, MICHAEL HARTNETT, a citizen of the United States, residing at Milton, in the county of Northumberland and State of Pennsylvania, have invented certain new and useful Improvements in Railway-Ties, of which the following is a specification.

This invention relates to railway ties and particularly to such ties constructed in part of wood and in part of metal, whereby the rail supported thereon is insulated, and may therefore be used equally well on steam and electric roads and on roads where the automatic block signals are used.

The object of the invention is to provide such ties of simple and economical construction which may be very easily maintained after being once erected and put in use and with this object in view, the invention consists in the improved construction and arrangement of parts which will be hereinafter fully described and afterward specifically pointed out in the appended claims.

In order that the construction and operation thereof may be readily comprehended, I have illustrated an approved embodiment of my invention in the accompanying drawings and will now proceed to fully and specifically describe the same, having reference to said drawings in which—

Figure 1 is a view of my improved tie in elevation in position to support a pair of rails which are shown in section, mounted thereon.

Fig. 2, is a top plan view of the structure shown in Fig. 1.

Fig. 3, is a sectional view of the same on a longitudinal, vertical plane cutting centrally through the tie and rails shown in Figs. 1 and 2.

Fig. 4, is a sectional view on the transverse vertical plane indicated by the broken line 4—4 of Figs. 1, 2 and 3.

Fig. 5, is a view, in elevation of one of the two wooden blocks used in the construction of my tie.

Fig. 6, is a view, in end elevation, of one of these blocks.

Like reference characters mark the same parts wherever they appear in a plurality of the figures of the drawings.

Referring specifically to the drawings, 7 indicates the metallic base of the tie, of trough-like form, extending the whole length of the tie, being transversely corrugated in its lower surface, as at 8, in order to prevent any slipping of the tie longitudinally, and transversely of the length of the rails.

60 The sides of the trough are indicated at 9, its ends at 10 and small tops extending only a short distance from the ends, at 11.

The sides 9 are cut away at 12, 13, leaving the central portions, at 14, of full height. 65

At 15, 16 are blocks of wood which are fitted in the trough near each end, the outer ends 17 of these blocks fitting under the tops 11, both ends 17 and 18 being reduced in vertical dimension to the depth of the 70 trough of the tie.

Between the inner ends of the blocks 15 and 16, a metal cap 18^a is fitted, having side flanges 19 which engage over the upper edges of the trough.

75 A screw bolt 20 has its head 21 in a T slot in the bottom of the trough and passes up through the trough and the center of the cap 18^a, and a nut 23 threaded upon the upper end of the bolt bears upon the top 80 of the cap and holds it in position.

The ends of the cap 18^a bear on the reduced inner ends of the wooden blocks and as the outer ends of the blocks are under the tops 11, said blocks are firmly held by the 85 bolt 20 against displacement.

Rails 24, 25 are spiked upon the wooden blocks, either with or without the tie plate sometimes used, preferably with the tie plate, to keep the block dry so that it will 90 not decay as fast as it would without the tie plate.

The wooden blocks act as cushions in the tie and allow for expansion and contraction, as well as allowing the current on electric 95 roads to travel undisturbed through the rail.

The amount of wood for one tie as described will be less than one-third of the wooden tie now in use. The wooden blocks can easily be removed by removing the steel cap 100 from the body of the tie, and lifting a block out when to be removed. The life of this tie will be from fifteen to twenty-five years, the drier the climate the longer the life of the tie. The tie having a corrugated bottom it 105

cannot slip or work out of line, and the cost of maintenance in labor will be as one man to the greater force required with the present wooden tie. The bolt holding the cap is very easily replaced in case it should break 110 as its head fits in a T slot in the bottom of the tie, and can be slipped out and removed.

Having thus fully described my invention, what I claim and desire to secure by Letters Patent of the United States is:—

1. A railway tie comprising a trough-like metallic body open at the top except for end caps, wooden blocks in the trough having reduced outer ends fitting under the caps, and means for securing the inner ends of both the blocks comprising a metal cap engaging over said inner ends and the upper edges of the sides of the trough, a bolt with its head attached to the bottom of the trough and passing through the cap, and a nut on the bolt bearing on the top of the cap.
- 10 2. A railway tie comprising a trough-like metallic body open at the top except for end caps, wooden blocks in the trough having reduced outer ends fitting under the caps, and means for securing the inner ends of the blocks comprising a metal cap resting upon the inner ends of the blocks and the upper

edges of the trough, and a bolt securing the cap to the bottom of the trough.

3. A railway tie comprising a metallic trough having closed ends and a small cap 25 over the top of each end, wooden blocks having their outer ends under said caps, a central steel cap resting upon the inner ends of the blocks, and a bolt to hold the cap in place.

4. A railway tie comprising a metallic trough having a T groove in the central portion of its bottom, wooden blocks in the ends of the trough, a metallic cap on the central portion of the trough resting on the inner 35 ends of the blocks and having edge flanges engaging over the upper edges of the trough sides, a bolt having its head in the T slot and passing through the cap, and a nut on the bolt above the cap.

In testimony whereof I affix my signature.

MICHAEL HARTNETT.
